CLAIM

The ornamental design for a cinch for earbud and earphone cords, as shown and described.

DESCRIPTION

FIG. 1 is a perspective view of a cinch for earbud and earphone cords in accordance with our new design;

FIG. 2 is a front elevation view thereof;

FIG. 3 is a rear elevation view thereof;

FIG. 4 is a top plan view thereof;

FIG. 5 is a bottom plan view thereof;

FIG. 6 is a left side elevation view thereof; and,

FIG. 7 is a right side elevation view thereof.

The dashed lines in the drawings are for illustrative purposes only and form no part of the claimed design.

1 Claim, 4 Drawing Sheets
